UNITED STATES PATENT OFFICE.

THEODORE J. GARISIO, OF ALLENTEOWN, PENNSYLVANIA.

DOUP.

Application filed April 11, 1925. Serial No. 22,351.

To all whom it may concern:

Be it known that I, THEODORE J. GARISIO, a citizen of the United States of America, and a resident of Allentown, Lehigh County, Pennsylvania, have invented certain new and useful Improvements in Doups; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention relates to doups, which may be used in the manner of my prior Patent No. 819,420 of May 1, 1906, for making centre selvages on piece goods, and also for making lines of so-called hemstitching or 20 fagoting along the length of the goods, there being as many doups used as there are to be longitudinal rows of hemstitching or fagotting across the width of the goods.

This is mostly done in silk piece goods, 25 and forms longitudinal stripes, the design of which can be varied by including a greater or less number of warp threads, as well as a greater or less number of weft threads in each fagot thread loop.

30 In fine goods, such as silk, the wire of the doup must be of very small gauge and the eye in the fagot thread carrier must also be small; and there is apt to be a hanging or catching of the warp threads in the 35 angle between the fagot thread eye and the lifter for the carrier. This I have avoided.

It is also noticed that the sinuous fagot thread at times feeds too fast, and irregularly, or hangs on the supply spool so that it 40 often breaks, and I have provided means that prevents this by releasing the thread from the spool say a fraction of a turn, so as to allow the fagot thread to feed at will without too great restraint, so that there 45 will be no danger of this fine thread breaking as it alternately passes through the shed first on one side and then on the other side of a set of warp threads.

Referring to the drawings, in which like 50 parts are similarly designated:

Figure 1 shows a vertical transverse section of so much of a silk loom as will be necessary to an understanding of my invention, with my attachment applied thereto.

Fig. 2 is a side view of the doup, about 55 one-half the size.

Fig. 3 is an enlarged view of the upper end of the fagot thread carrier, illustrating more clearly the lower bent ends of the 60 lifters.

Referring to Figure 1, I have shown a portion of a loom in which the heddle frames 5, any number of which may be used, carry the usual heddles 6. Each heddle frame 5 is connected to a lifter cord 7 that goes to the 65 dobbay or the jacquard, as the case may be. The frames are retracted by springs 8. 9 is the goods beam, 10 the batten, 11 the reed, 12 the warp, 13 the warp guide and 14 the 70 warp beam, all of usual construction and well known arrangement.

The loom is a top shed loom, although an open shed or a bottom shed loom may be fitted with my attachment.

The fagot thread carrier 15 is made of a 75 length of wire and has a very small eye 16 at the top of a long loop 17 that is substantially symmetrical to a longitudinal axis of the loop. The eye is turned downward toward the interior of the loop. The upper 80 part of this loop 17 is more ovate or less tapering than the lower part, the two ends of the wire are then twisted together at 18 below the loop, and one of these end terminals below the twisted portion, terminates 85 in an eye 19. The eye 19 is connected to a retracting spring 20 or a lingo, as desired.

The length of the loop 20 must be such when passing through the warp during the 90 making of the shed and while supporting the fagot thread in its upper position that the warp threads shall, preferably, not rub over the twisted shank 18 of the loop.

The loop has two lifters 20 and 21, each 95 also consisting of a single wire having a loop 22 at its lower end, the ends of the wires being then twisted together to form a shank, and terminating in an eye 23. This eye 23 is connected to a cord 24 going to the jacquard or dobbay.

It will be noted that each lifter loop 22 is bent at an angle at its lower end at 25, so that when the lifter is raised the lower bent end 25 (Fig. 3) rests in the angle between the fagot thread eye and that side of the 105 carrier loop to which the lifter is connected. This allows the body of the lifter to hang vertically and the fagot carrier also to hang

vertically without forming an acute angle between the top of the fagot thread eye and the lifter loop 22 that can catch a silk warp therein and cause it to break as the carrier 5 is lifted through the warp. This permits the use of my device with fine silks and other sheer fabrics.

The fagot thread 26, Fig. 1, may feed irregularly, notwithstanding that it is provided with a tensioning weight 27 consisting, in my construction, of a small block of wood. This block of wood has a vertical slot 27^a and is mounted to slide on a staple-shaped wire guide 28. The weight carries 15 a pigtail thread guide 29. Said guide 28 is driven into a frame 30 consisting of an angle-shaped piece of wood provided with a hook-shaped piece of iron 31 screwed through one leg to the rear edge of the vertical shank of the frame 30.

A set-screw 32 passes through the other, free, shank of the hook and serves to fasten the frame 30 in any position transversely of the loom on a bar 33 on the back of the 25 loom.

A pin 34 is secured to the horizontal leg of the frame 30, and carries the spool 35 for the fagot thread. This spool is free to rotate and is held on its pin 34 by a 30 cotter pin 36.

Projecting from the spool, preferably from the head adjacent the frame 30, are pins 37, one or more of which may be used, according to requirements.

35 Mounted on a screw 38 is a lever 39 of wire, having a horizontal stop portion 40 projecting into the path of the pins 37, and the front end of this lever is formed as a hook 41 passing through the staple guide 28 40 which limits the upward movement of the lever. The lever rests on pigtail thread guide 42.

There is a third pigtail 43 at the front of the frame 30.

45 The sliding weight 27 is chosen for the lightest thread, but may be used with heavier thread, and for this purpose an eye 44 is screwed into the bottom of the block 27 on which may be hung a lingo 45.

50 The operation is as follows:

Assume that a group of two or more warp threads 12 are to be crossed by the fagot thread 26. These warp threads pass between the two lifters 20 and 21, and the fagot thread is passed from spool 35 through the pigtail 42, 29 and 43 in succession, the eye 16 of the lifter and the reed to the goods beam. After a given number of weft threads have been inserted in the warp, 55 the carrier 15 is raised through the warp by one of the lifters, say 20, on one side of the chosen group of warp threads, then additional weft threads are inserted and the lifter is lowered. The spring 20' pulls the 60 lifter below the warp and the lifter 21 raises 65 the carrier on the other side of the group of warp threads; a number of weft threads are again inserted in the warp, the lifter 21 is lowered, the carrier 15 remains below the warp until more weft threads are inserted, 70 and the operations are repeated.

75 In this manner the fagot thread forms a sinuous weave alternately from right to left and vice versa across the warp threads, including both warp and weft threads.

The pattern is varied by varying the number of warp threads included in the group, and by varying the number of weft threads inserted in the warp between each crossing of the fagot thread.

80 There are as many doup mechanisms used as there are longitudinal rows of fagoting in the width of fabric.

For making a centre selvage on a broad silk loom only two such mechanism may be 85 used.

90 In case the fagot thread does not feed well, and to prevent the fagot thread from feeding too fast by reason of the tension thereon during the crossing of the fagot thread, and as this thread is used, the spool rotates until a pin 37 strikes the stop 40 and is held thereby, the weight 27 then rises until it strikes the hook 41, lifts the wire lever 39 from support 42, releases pin 37, and allows 95 (in the particular structure shown) the spool to make a half turn. The release of the spool permits the weight 27 to drop and the lever to return to its checking position supported by the shank of pigtail 42.

100 It will be understood that various modifications may be made in the construction without changing the nature of the invention.

I claim:—

1. In a doup, the combination with a thread carrier having an eye; of a metal lifter having a loop at its lower end, the lower end of said loop being bent from the plane of the loop outwardly.

110 2. In a doup, the combination with a thread carrier comprising a loop having a thread eye at its top; of a lifter for said carrier having a loop at its lower end through which one side of the loop of the carrier passes, the lower end of the lifter loop being bent outwardly from its plane to permit the lifter loop to make an obtuse angle with the top of said eye.

115 3. In a doup, the combination with a thread carrier comprising a wire loop having a thread eye directed downwardly between the sides of the loop; of two wire lifters each having a loop on its lower end through which a side of the carrier loop passes, and each lifter loop being bent at its lower end outwardly from the vertical axis of the carrier loop.

120 4. The combination with a doup; of a removable frame for attachment to a loom,

a spool on said frame and mounted to rotate, a weight for the spool thread, means to hold the spool against rotation, and means operated by said weight to operate the spool holding means to release the spool.

5. The combination with a doup; of a frame for attachment to a loom, a spool rotatably mounted on said frame, a weight for the spool thread and a pivoted stop member for the spool operated by the weight to release the spool.

10. The combination with a doup; of a frame, means to permit the frame to be adjusted in any transverse position of the loom in accordance with the position of the doup, a spool rotatably mounted on said frame, a weight vertically guided on the frame, a pin on said spool, and a stop lever arranged to be engaged by said pin, said 15 lever arranged to be actuated by said weight and said weight being actuated by the thread from the spool to the doup.

20. The combination with a doup; of a frame, a spool rotatably mounted on the frame, pins on said spool, a stop lever pivoted to the frame and having a stop for engagement by said pins, a vertical guide on said frame, and a weight having a vertical slot for the guide, said lever arranged in 25 the path of said weight and limited in its upward movement by said guide.

25. The combination with a doup; of a frame, a spool rotatably mounted on said frame, pins radially projecting from said spool, a stop lever pivoted to said frame and having a stop to be engaged by said pins a 30 staple-shaped vertical guide, a slotted

weight mounted to vertically slide between the guide and frame, a hook on one end of said lever and passing through the guide in 40 the path of said weight, and a lingo attached to the weight.

45. The combination with a doup; of a frame, means to adjust the frame transversely of a loom, a spool rotatably mounted on the frame, pins projecting radially from the spool, a stop lever having a stop to be engaged by said pins, a vertically guided weight, a thread guide on the frame supporting said lever and a thread guide on the weight, said lever projecting into the path of said weight and lifted thereby off its supporting thread guide out of the path of said pins, said weight being lifted during 50 the action of the doup.

55. The combination with a doup; of a frame, means to adjust the frame transversely of a loom, a spool on the frame, pins radially projecting from the spool, a stop lever pivoted at one end to said frame and having a stop projecting in the path of said lever, a vertically slidable weight having a vertical slot, a staple-like guide in said frame and engaging the slot, a thread guide in the frame and supporting the lever, said lever having a hook projecting through the weight guide and in the path of the weight, a thread guide on the weight, a third thread guide near the forward edge of the frame and a detachable lingo for the weight.

60. In testimony that I claim the foregoing as my invention, I have signed my name hereto.

65. THEODORE J. GARISIO.
